(57) **CLAIM**

The ornamental design for a vehicle cargo light, as shown and described.

DESCRIPTION

FIG. 1 is a perspective view of an embodiment of a vehicle cargo light;

FIG. 2 is a front view of the embodiment of a vehicle cargo light of FIG. 1;

FIG. 3 is a rear view of the embodiment of a vehicle cargo light of FIG. 1;

FIG. 4 is a left-side view of the embodiment of a vehicle cargo light of FIG. 1;

FIG. 5 is a right-side view of the embodiment of a vehicle cargo light of FIG. 1;

FIG. 6 is a top view of the embodiment of a vehicle cargo light of FIG. 1;

FIG. 7 is a bottom view of the embodiment of a vehicle cargo light of FIG. 1; and,

FIG. 8 is a front view of the embodiment of a vehicle cargo light of FIG. 1 installed on a rear window of a vehicle viewed from inside the vehicle.

The dash-dash broken lines in the drawings depict portions of the vehicle cargo light that form no part of the claimed design. The dot-dash broken lines represent environment and forms no part of the claimed design.
